UNITED STATES PATENT OFFICE.

FREDERICK WM. YOUNG, OF HARTFORD, CONNECTICUT.

FLASH AND RECOIL REDUCER FOR FIREARMS.

1,342,978.

Specification of Letters Patent.

Patented June 8, 1920.

Application filed March 10, 1919. Serial No. 281,589.

To all whom it may concern:

Be it known that I, FREDERICK W. YOUNG, a citizen of the United States of America, and a resident of Hartford, Connecticut, have invented certain new and useful Improvements in Flash and Recoil Reducers for Firearms, of which the following is a specification.

The object of this invention is to provide an attachment suited to firearms of various types, including machine-guns and rifles, which will conceal the flash, reduce the recoil and muffle the report. A further object is to provide a form of construction in which metal tubing may be employed with a minimum of machinework thereon.

In the accompanying sheet of drawings which forms a part of this application—

Figure 1 is a longitudinal section through the attachment together with a view of the end of the barrel of a firearm to which it is attached, and

Fig. 2 is a cross section on the line II—II of Fig. 1.

25 The attachment comprises a tubular casing 3 interiorly threaded at the rear end 4 for securing it to the muzzle of a firearm 5. Forward of this securing thread the bore is enlarged to form an expansion chamber 6, 30 and in front of this, inside the casing is a helical baffle which is rigid with the casing and preferably though not necessarily of one piece of metal therewith. It is formed by cutting a deep groove which constitutes 35 a helical baffle chamber open to an axial passage for the bullet in line with the axis of the barrel. The helical baffle chamber is preferably divided off from the expansion chamber in order to leave metal for in-

40 creased strength at the rear, but may be cut out at the forward end. The portion of the axial passage formed by the inner edge of the helical baffle preferably has a slight taper, being smaller at the forward end, so that 45 each successive convolution of the helical baffle will have its proper share of the baffling action and not be wholly screened by the convolutions behind. The taper is also useful in manufacturing and in securing alignment. Midway of the helical baffle chamber, one or more gas-outlets 8, 8 lead through 50 the tubular casing and serve as outlets for the other convolutions as well as the one with which they communicate. That they 55 may be sufficiently large so as not to clog readily and yet have the flow through them

impeded sufficiently for proper action, the tubular casing is surrounded by an outer tubular baffle 9 which is secured to the tubular casing at the rear by threads 10. This 60 provides an annular impedance passage which is sufficiently narrow and sufficiently long to materially check the flow through the gas-outlets, for the reduction of the flash is found to depend upon the impedance 65 in this annular passage. The impedance is preferably further increased by an intermediate tubular baffle 11 which is secured preferably by a forced fit to the tubular casing at the forward end 12, and for the 70 balance of its length has a slightly larger bore than the outside diameter of the tubular casing so as to leave a second annular impedance passage which leads at its rear end into the other impedance passage. The 75 outer tubular baffle has an inturned flange at its forward end. By having two tubes and two annular impedance passages, the gas is caused to flow first rearwardly to the 80 end of the intermediate tubular baffle, then forwardly between the intermediate and outer tubular baffles and finally radially at the mouth of the device thereby increasing the impedance and further reducing the 85 flash.

What I claim, is—

1. A flash and recoil reducer for firearms comprising a tubular casing adapted to be secured to the muzzle of a firearm and containing a helical baffle with the convolutions 90 rigidly connected to the casing and forming an axial passage in line with the bore of the barrel and a helical baffle chamber surrounding and open to the axial passage.

2. A flash and recoil reducer for firearms 95 comprising a tubular casing adapted to be secured to the muzzle of a firearm and containing a helical baffle with the convolutions rigidly connected to the casing and forming a tapered axial passage in line with the bore 100 of the barrel and a helical baffle chamber surrounding and open to the axial passage.

3. A flash and recoil reducer for firearms comprising a tubular casing adapted to be secured to the muzzle of a firearm and containing an expansion chamber and a helical baffle forming an axial passage in line with the bore of the barrel and a helical baffle chamber divided off at its rear end from the expansion chamber and open to the axial 110 passage.

4. A flash and recoil reducer for firearms

- comprising a tubular casing adapted to be secured to the muzzle of a firearm and containing a helical baffle with the convolutions rigidly connected to the casing and forming an axial passage in line with the bore of the barrel and a helical baffle chamber closely surrounding and open to the axial passage, the helical chamber being provided with a gas-outlet through the casing about midway 10 of its length.
5. A flash and recoil reducer for firearms comprising a tubular casing adapted to be secured to the muzzle of a firearm and containing a baffle forming an axial passage in line with the bore of the barrel and a baffle chamber within the casing, a tubular baffle surrounding the casing and secured to it at the rear end and forming an axial passage in line with the bore of the barrel and a baffle chamber within the casing, an outer tubular baffle surrounding the casing and secured to it at the rear end, an intermediate tubular baffle secured to the casing at the forward end and projecting rearwardly into the space 45 between the tubular casing and the outer tubular baffle and forming inner and outer impedance passages which communicate at their rear ends and in which the outer passage has an annular vent at its forward end, 50 and a gas-outlet connecting the baffle chamber and the inner impedance passage.
- 15 8. A flash and recoil reducer for firearms comprising a tubular casing adapted to be secured to the muzzle of a firearm and containing a baffle forming an axial passage in line with the bore of the barrel and a baffle chamber within the casing, an outer tubular baffle surrounding the casing and secured to it at the rear end, an intermediate tubular 55 baffle secured to the casing at the forward end and projecting rearwardly into the space between the tubular casing and the outer tubular baffle and forming inner and outer impedance passages which communicate at 60 their rear ends and in which the outer passage has an annular vent at its forward end directed toward the axial passage, and a gas-outlet connecting the baffle chamber and the inner impedance passage. 70
- 20 6. A flash and recoil reducer for firearms comprising a tubular casing adapted to be secured to the muzzle of a firearm and containing a baffle forming an axial passage in line with the bore of the barrel and a baffle chamber within the casing, a tubular baffle closely surrounding the casing and secured to it at the rear end and forming an axial passage in line with the bore of the barrel and a baffle chamber within the casing, an outer tubular baffle surrounding the casing and secured to it at the rear end, an intermediate tubular 65 baffle secured to the casing at the forward end and projecting rearwardly into the space between the tubular casing and the outer tubular baffle and forming inner and outer impedance passages which communicate at 70 their rear ends and in which the outer passage has an annular vent at its forward end directed toward the axial passage, and a gas-outlet connecting the baffle chamber and the inner impedance passage.
- 25 7. A flash and recoil reducer for firearms comprising a tubular casing adapted to be
